CLAIM

The ornamental design for a combined hose and flow line coupling member, as shown and described.

DESCRIPTION

FIG. 1 is a side view of the combined hose and flow line coupling member, the opposite side being a mirror image; FIG. 2 is a rear view of the design in FIG. 1; FIG. 3 is a front view of the design in FIG. 1; and, FIG. 4 is a front perspective view of the design in FIG. 1. The broken line showing is for illustrative purposes only and forms no part of the claimed design.
